TELEVISION APPARATUS

William Hoyt Peck, New York, N. Y.

Application October 5, 1934, Serial No. 747,057

4 Claims. (Cl. 178—6)

This invention relates to television systems, to television transmitters, and more particularly to television transmitters for scanning the areas of a strip of photographic film, such as a reel of motion or talking picture film.

An object of the invention is to provide an improved form of television scanning apparatus for creating in an electrical circuit, a current varying in amplitude in correspondence with the variations in opacity of contiguous elementary areas constituting in aggregate the entire photographic area of a strip of film.

A feature of the apparatus resides in the fact that it employs no gears or intermittent drive. The apparatus is thus of extremely simple construction as compared to known systems of the same character. Moving parts are reduced to a minimum. For both of these reasons the operation is noticeably quiet and free from vibration.

The apparatus is adapted to scan simultaneously both the sound track and the picture portions of talking picture film. This necessitates maintaining great uniformity of film feed at the point of scanning to prevent distortion in the process of scanning such as is particularly noticeable in the reproduced sound effects. In accordance, therefore, with a further object of the invention the requisite uniformity of film feed is secured by passing the film strip at the point of scanning over relatively massive idling rollers mounted on ball bearings, the housings of which are packed with a viscous medium, such as a heavy high heat grease in contact with relatively large areas of the fixed and movable bearings races. The mass of the rollers is sufficient to maintain them rotating uniformly despite momentary fluctuations in tension in the film due, for example, to variations in speed of the driving sprockets. The viscous packing on the other hand provides a slight braking action which maintains the film under proper tension as it passes over the idlers.

In its essentials the apparatus of the invention employs a tubular stationary shaft and a parallel motor driven rotatable or driving shaft. The tubular shaft has formed in its cylindrical surface, a pair of axially displaced scanning apertures, one of which forms part of the picture scanning mechanism, while the other aperture is similarly utilized for scanning the sound track of the film.

The picture and sound track portions of the film are separately scanned although simultaneously, by feeding the film a plurality of times from the driving shaft about the tubular shaft.

To this end the tubular shaft is provided with a plurality of the aforesaid spaced idling rollers coaxial with the shaft and in viscous bearing contact therewith as stated. One pair of rollers is so disposed that the film in one passage about the shaft has its picture portion fed past the picture scanning aperture disposed between the rollers. A second pair of rollers axially displaced from the first feeds the sound track of the film in a second passage about the shaft past the sound track aperture therein.

The film, supplied from a first reel and rewound on a second reel, is driven by sprockets keyed to the driving shaft, the sprockets having teeth adapted to engage the perforations along the edge of the film as it is fed successively from the driving to the tubular shaft.

Scanning of the picture and sound track portions of the film is accomplished by a pair of optical systems, each employing a light source, a photoelectric element together with suitable light reflecting and focusing elements for directing a scanning beam from the proper source through the film onto the associated photoelectric element. The photoelectric elements are conveniently mounted within the tubular shaft beneath the picture and sound apertures respectively.

A fixed optical system, i. e., one employing no moving parts, suffices for scanning the sound track. For this purpose the light source and focussing elements are disposed in a tubular housing external to the tubular shaft and positioned to focus a beam of constant intensity on the film at the sound aperture.

A somewhat similar arrangement is utilized for scanning the picture, with the exception that in this instance, the scanning beam is variably deflected transversely of the film by a light reflecting rotatable scanning member. This is conveniently accomplished in accordance with the invention, by keying the rotatable scanning member to the shaft of a separately driven motor having its axis of rotation in a plane perpendicular to the axis of the tubular shaft.

The rotatable scanning member may be of a known construction employing a multiplicity of mirror elements suitably disposed at proper inclination about the periphery thereof for causing the scanning beam to traverse the film in a succession of contiguous transverse paths. Preferably, however, the scanning member employs the principles of construction described and claimed in my copending application Serial No. 601,495, filed March 28, 1932, wherein the scan-

ning elements are sections of convex lenses having preferably anterior surfaces of spherical contour, and plane posterior surfaces which are mirrored. These lens elements are so disposed about the periphery of the rotatable member that the scanning beam impinges normally on the curved anterior surface of each lens while it intercepts the beam, the beam being totally reflected internally at the plane mirrored posterior surface of the lens normally back through the anterior surface. The lens thus serves the dual role of variably deflecting the beam for scanning and of distortionlessly focussing the beam at the film surface, all as is fully described in my said copending application and referred to herein-after.

In the process of scanning with the apparatus and subsequent recreation of the image with receiving apparatus, the recreated image may not be properly "framed" on the screen. To eliminate this defect the stator of the motor which drives the film feed is, in accordance with the invention, so mounted as to be rotatable within proper limits by a manually actuated worm gear. Thus by simply rotating the stator of the driving motor, an image thrown on the screen of a receiving apparatus may be vertically displaced up or down on the screen until it is properly "framed."

Referring to the drawings:

Fig. 1 is a front elevation of apparatus in accordance with the invention for scanning the picture and sound track of talking picture film.

Fig. 2 is a rear elevation of the apparatus, and Fig. 3 a plan view as viewed from above and facing to the right in Fig. 2.

Fig. 4 is an enlarged plan view of the film feed mechanism for scanning as viewed from above and facing to the right in Fig. 1.

Figs. 5 and 6 are at 5—5 and 6—6 respectively of Fig. 4.

Fig. 7 is a plan view of the scanning disc as viewed from below in Fig. 6 with the hemispherical housing removed.

Fig. 8 is a section at 8—8 of Fig. 6.

Figs. 9 and 10 are sections at 9—9 and 10—10 of Fig. 6.

Fig. 11 is a section at 11—11 of Fig. 4, and Fig. 12 a horizontal section at 12—12 of Fig. 11.

Fig. 13 is a diagrammatic showing of the optical systems for scanning of the picture and sound track of the film.

Referring to the drawings the entire scanning apparatus is mounted on a panel 1 supported by a stand 2. The strip of film 3 to be scanned is unwound from a reel 4 and rewound on a second reel 5, the reels being housed in a standard manner in drum casings 6 and 7 respectively carried by panel 1 and provided with hinged covers as shown for affording access to the reels. The take-up reel 5 is driven from a motor 8, Fig. 2, by means of belt 9 passing over pulleys 10 and 11 keyed to the motor and reel shafts respectively.

For purposes of scanning, the film, in passing from reel 4 to reel 5, is fed a plurality of times about a pair of parallel shafts 12 and 13, Fig. 4. To this end shaft 12, which is a tube affixed to and projecting from panel 1, has arranged coaxial therewith a plurality of axially spaced film idling rollers 14, 15, 16, 17 rotatably mounted on shaft 12 by the interposed ball bearings such as 18. The film 3 in one passage over shaft 12 is guided between shoulders 19, 20 of and over rollers 14, 15. Similarly in a succeeding passage over shaft 12, the film is guided between shoulders 21, 22 of and over rollers 16, 17.

Shaft 13, passing through bearings in panel 1, is coupled directly to the rotor shaft of motor 8. The feeding of the film is effected by sprockets such as 23, 24, Figs. 6 and 11, keyed to shaft 13, the sprockets being provided with peripheral teeth as shown for engaging the lateral film perforations.

The film strip 3 after leaving reel 4, Fig. 1, passes over a sprocket of shaft 13 at the left in Fig. 4, thence Fig. 6, it passes between a resilient guide 25 and an idler 26 to the under side of and around rollers 14, 15 of shaft 12, Fig. 5, to sprocket 23 on shaft 13, Fig. 6, and back Fig. 11, between resilient guide 27 and roller 28 to the under side of and around rollers 16, 17 of shaft 12, Fig. 5, to sprocket 24, Fig. 11, over a roller 29, thence under and across and back over a sleeve 30 keyed to shaft 12, Figs. 4 and 5, through the second sprocket from the left on shaft 13, Fig. 4, to the film rewind reel 5, Fig. 1.

A uniform rate of film feed over rollers 14, 15, 16, 17, irrespective of fluctuations in the speed of shaft 13, due for example to variations in the driving torque of motor 8, is secured by making the idling rollers 14, 15, 16, 17, relatively massive and by the provision of a viscous packing 31, Fig. 5, such as a high heat grease or the like, filling the space between the movable 32 and fixed 33 races for the ball bearings 18. The provision of this viscous packing, which, as stated, constitutes a feature of the invention, has, employed in the bearing housings of the relatively heavy idling rollers, proved in practice to afford a highly satisfactory means of maintaining the film feed sufficiently uniform to eliminate signal distortion in the process of scanning.

Referring to Figs. 6, 9, 10, the film perforations are constrained by idling rollers such as 34, 35, to engage the teeth of sprocket 23 continuously as the film is fed over the sprocket. To facilitate threading of the film, rollers 34, 35, are mounted at opposite ends of lugs and between a pair of spaced brackets 36, 37, centrally pivoted by means of a tie rod 38, at 39, to a cam 40, which in turn is pivoted at 41. Upon manipulation of a lever 42 affixed to cam 40, rollers 34, 35 may be withdrawn from engagement with the film by the eccentric action of the cam. In order, however, to insure a locking engagement of rollers 34, 35 with the cam in the position of Fig. 6, the cam is provided with a notch 43 into which a resiliently housed pin or ball bearing 44, Fig. 9, slips when the cam is in the locking position. Similar cam and lever arrangements are employed for disengaging rollers such as 26 from the film strip as is illustrated in Figs. 6 and 10. A roller, such as 44, assists in maintaining the film under constant tension.

As part of the scanning mechanism the cylindrical surface of shaft 12 is provided with a pair of axially displaced scanning apertures 45 and 46, Fig. 5. Aperture 45 is of a width sufficient to embrace the picture portion 47, Fig. 4, of the film for scanning; while aperture 46 is sufficiently large to embrace the sound track 48, Fig. 4. Rollers 14, 15 are spaced axially as shown sufficiently to prevent obstructing aperture 45 and are so disposed as to guide the picture portion of the film past the aperture. Rollers 16, 17 are similarly axially spaced sufficiently to prevent obstructing aperture 46, and are so disposed with respect to the aperture as to guide the sound track of the film past the aperture.

Scanning of the picture portion of the film is effected by the optical system illustrated dia-

grammatically in Fig. 13, and structurally more particularly in Figs. 6, 7 and 8. It employs a light source 49, such as an electric lamp, the filament of which in series with a variable resistance 50, is energized from a suitable electrical power source connected to terminals 51. In its essentials the system comprises the lamp arranged to direct a ribbon beam through an optical slit 52, normally onto the face of a right prism 53, from the hypotenusal face of which the beam is totally reflected internally normally through the third face of the prism onto a light reflecting and focussing element 54 of a rotary scanning member 55 described hereinafter. Element 54 of the scanning member directs and focusses the beam at the film strip 3, Figs. 5 and 6, as it passes over slot 45. The luminosity of the beam passing through the film is concentrated by a lens 56, arranged in aperture 45, onto a photo-electric element 57 disposed within tubular shaft 12 beneath aperture 45.

The scanning member 55 is constructed, as stated, in accordance with the principles described in my copending application Serial No. 601,495, filed March 28, 1932. The scanning member, of conical contour, has disposed about it at equal inclinations to its axis of rotation, a plurality of scanning elements 45 of identical construction and configuration. Each element is a section including the optical axis of a convex lens and is preferably a section of a hemispherical lens so disposed on member 55 that the beam reflected from prism 53 impinges normally on the spherical anterior surface 48 of the lens and thus traverses the lens in a converging radial beam intersecting its optical axis at the plane posterior surface which is mirrored over a circular area 49 for reflecting the entering beam normally back through the anterior surface in a beam converging to a focus at the film strip 3.

Member 55 is mounted on the shaft 60 of a motor 61 having its axis of rotation situated in a plane substantially perpendicular to the axis of shafts 12 and 13. Accordingly as member 55 rotates, each lens 54, as it cuts across the beam reflected from prism 53, deflects a focussed image of an elementary portion thereof transversely across the film strip. As the lens in question rotates beyond the luminous field of the beam, the lens next adjacent enters the field and deflects a second beam transversely of the film, and so on for each succeeding lens.

As these beams move in succession across the film, the film meantime is fed, in the manner described, continuously in a direction at right angles to the path traversed on the film by the deflected scanning beam. Accordingly the successive scanning beams trace a succession of contiguous transverse paths on the film thereby to scan successively every elementary photographic area thereof.

Photocell 57, thus subjected to a luminous intensity varying from instant to instant inversely as the opacity of contiguous elementary areas of the film scanned, translates these luminous intensity variations into an electrical current varying correspondingly in amplitude.

Lamp 49, optical slit 52, and prism 53 are mounted in alignment on a tubular housing 62, Fig. 6, affixed to a plate 63, Fig. 1, supported by panel 1. Motor 61 is likewise mounted on plate 63. The optical slit is formed by cooperation of a member 64, Figs. 6 and 8, extending longitudinally of housing 62, and a transverse member 65

laterally adjustable to determine the width of the slit.

The lens elements 54 are affixed to the scanning member 55 by screws, such as 66, for adjusting the lenses to a proper inclination, after which the lenses are permanently cemented in place in a suitable medium 67. The scanning member is covered by a removable housing 68 provided with suitable apertures 69, 70 for passage of the scanning beam.

The optical system for scanning the sound track of the film is illustrated schematically in Fig. 13 and structurally in Fig. 12. A beam from a source 71, such as a lamp connected to terminals 51, as focussed by a condensing lens 72 at 15 a small slotted aperture of a diaphragm 73. A second condensing lens 74 focusses a luminous image of the slotted aperture on the sound track of the film strip 3. The beam transmitted through the film is directed through the aperture 20 of a second diaphragm 75 disposed in aperture 46 of shaft 12, Fig. 5, onto a second photoelectric cell 76 disposed within tubular shaft 12 adjacent photocell 54. As the film strip is fed uniformly over idlers 16, 17 in the manner explained, the beam intercepts successive portions of the sound track whereby the current flowing through photocell 76 varies in amplitude in correspondence with the variations in opacity of the sound track.

Elements 71, 72, 73 and 74 of the optical system are disposed in alignment in a tubular housing 77 provided with a cover 78 for access to lamp 71. This housing is supported on plate 63, Fig. 1, adjacent housing 62 of the picture scanning optical system.

Referring to Figs. 2 and 3, the stator housing of motor 8 is rotatably supported at one end by panel 1 and at the opposite end by brackets 78 secured to the panel. Extending peripherally about the stator are teeth 79 meshing with a worm gear 80 keyed to a shaft 81, actuated by a handwheel 82. This mechanism provides a means of "framing" the television image projected on the screen of a receiving system. Rotation 45 of the stator clockwise or counterclockwise by manipulation of wheel 82, "frames" the picture up or down as desired.

Meters 83 and 84, Fig. 1, serve to indicate the filament currents of lamps 49 and 71 respectively.

I claim:

1. Television apparatus for scanning a strip of motion picture film containing a sound track comprising: a tubular member provided with a pair of spaced lateral apertures, means for continuously feeding the picture portion of said film past one said aperture and the sound track past the other, said means including film idling rollers rotatably supported on said tube adjacent said apertures, and a shaft paralleling said tube mounting spaced film sprockets whereby said film is fed a plurality of times from said sprocket about said tube, a pair of photoelectric elements disposed within said tube, means for directing a light beam through the picture portion of said film and the associated aperture onto one said photoelectric device, said means including a scanning device for causing said beam to traverse the picture portion of said film in contiguous transverse paths, and means for directing a second light beam through the sound track portion of said film and the associated aperture onto the second photoelectric element.

2. In a device for scanning a strip of motion

picture film containing a sound track: a tubular shaft containing a pair of spaced lateral apertures; means for feeding the picture and sound portions of said film uniformly past said apertures respectively, said means including a plurality of axially spaced idling rollers rotatably supported on said shaft, a driving shaft parallel to said tubular shaft, said driving shaft having keyed thereto a plurality of film sprockets whereby said film is fed a plurality of times between said driving and tubular shafts over said sprockets and idling rollers, a motor directly coupled to said driving shaft, and means associated with the apertures in said tubular shaft for scanning the sound track and picture portions respectively of said film.

3. In a device for scanning a strip of motion picture film containing a sound track: a tubular shaft containing a pair of spaced lateral apertures; means for feeding the picture and sound track portions of said film uniformly past said apertures respectively, said means including a plurality of axially spaced idling rollers rotatively supported on said shaft, a driving shaft parallel to said tubular shaft, said driving shaft having a plurality of film sprockets keyed thereto whereby said film is fed a plurality of times between said driving and said tubular shafts over said

sprockets and idling rollers, a motor directly coupled to said driving shaft, and means associated respectively with the apertures in said tubular shaft for scanning the sound track and picture portions of said film respectively.

4. In a device for scanning a strip of motion picture film containing a sound track: a tubular shaft containing a pair of spaced lateral apertures; means for feeding the picture and sound track portions of said film uniformly past said apertures respectively, said means including a plurality of axially spaced idling rollers rotatively supported on said shaft, a driving shaft parallel to said tubular shaft, said driving shaft having a plurality of film sprockets keyed thereto whereby said film is fed a plurality of times between said driving and said tubular shafts over said sprockets and idling rollers, a motor directly coupled to said driving shaft, said idling rollers being supported on roller bearings, a housing for said bearings, a viscous medium retained by said housing in contact with said shaft bearings and idling members for providing a braking effect during rotation of said idling members, and means associated with the apertures in said tubular shaft for scanning the sound track and picture portions respectively of said film.

WILLIAM HOYT PECK.
